UNITED STATES PATENT OFFICE

CHARLES B. GREENBERG, OF NEW YORK, N. Y.

SPRING-BAR ATTACHMENT FOR FLEXIBLE BRACELETS

Application filed January 28, 1929. Serial No. 335,493.

My invention relates to flexible bracelets and refers more particularly to the male spring bar attachment for the links of a flexible bracelet.

5 The object of my invention is to provide a simple, neat and attractive device that can be easily attached and detached from its co-operating parts.

I attain these results by the means illustrated in the accompanying drawings wherein similar numerals refer to like parts throughout the several views, in which:—

Figure 1 is an assembly of the device.

Figure 2 is an end elevation of the device.

15 Figure 3 is a detail of the spring bar pin.

Figure 4 is a detail of the spring bar tube.

Figure 5 is an assembly, partly in section of the spring bar.

20 Figure 6 is an isometric view of the bracelet link tube.

The device is made up of a spring bar unit and a bracelet tube which spring bar unit is commonly known as a male spring bar.

The bracelet link tube 1 is a tube circular 25 at 2 and has a rectangular extension at 3 and is somewhat shorter than the spring bar unit which is adapted to be held within the circular part of this tube by friction and the rectangular extension may be connected 30 to any other device such as 18 by means of extensions 19 and 20, which project into the rectangular opening 17.

The spring bar unit is comprised of a tube 4, one end of which is rounded and partly 35 closed to provide a hole 6 and the other end bevelled at 7, so that when its inner parts are assembled, this end 7 may be rolled over and form a hole at 8, as shown in Figure 5 and hold the working parts therein.

40 Within this tube are two spring bar pins 9 and 10, each comprised of a body portion 11 and a smaller extension 12, which extension is adapted to slidably engage with the holes 6 and 8 and the spring 13 will force 45 these pieces 9 and 10 against the partly closed ends of the tube 4.

In operation, the pins 9 and 10, providing pivots for that part 14 to which they may be attached, as shown by the dotted lines in 50 Figure 1, may be forced inwardly so that

they may be pivotally held by the bearings 15 and 16 of the part 14 and it is obvious that links or any other device may be easily attached to the rectangular part of the tube 1 in any suitable way.

Having thus described and illustrated the preferred embodiment of my invention, I do not wish to limit myself to the exact construction or arrangement of parts shown, since it is evident that modifications may be 60 made therein without departing from the spirit of the invention or scope of the claims.

I claim:—

1. In a male spring bar attachment, the combination with an inner tube with partly 65 closed ends slidably carrying two end pins and a spring adapted to press said pins apart and an outer tube of key hole shape in cross section formed to fit over said inner tube and having a rectangular side extension 70 adapted to hold any desirable device.

2. In a spring bar attachment for flexible bracelets, the combination of a tube of key 75 hole shape in cross section providing an extension, the round part of said tube adapted to hold a male spring bar provided with two slidable pivots.

3. In a spring bar attachment for flexible bracelets the combination of a tube of key 80 hole shape in cross section providing an extension, the round part of said tube adapted to hold a male spring bar comprised of a tube provided with two compressible pivots held therein between a spring means.

Signed at New York, in the county of New 85 York and State of New York, this 20 day of December, 1928.

CHARLES B. GREENBERG.
